UNITED STATES PATENT OFFICE

ELMER V. KLINE, OF UNIVERSITY CITY, MISSOURI, ASSIGNOR TO VICTOR PHARMACAL COMPANY, INC., OF ST. LOUIS, MISSOURI, A CORPORATION OF MISSOURI

DESIGN FOR A BOTTLE OR SIMILAR CONTAINER

Application filed July 8, 1931. Serial No. 40,459. Term of patent 14 years.

To all whom it may concern:

Be it known that I, ELMER V. KLINE, a citizen of the United States, residing at University City, St. Louis County, Missouri, have invented a new, original, and ornamental Design for a Bottle or Similar Container, of which the following is a specification, reference being had to the accompanying drawings, forming part thereof.

Fig. 1 is a perspective view of the bottle or similar container showing my new design.

Fig. 2 is a perspective view showing a cavity in the bottom wall of the bottle or similar container.

I claim:

The ornamental design for a bottle or similar container, substantially as shown and described.

ELMER V. KLINE.
